DESIGN FOR A SCREW

Henry F. Phillips, Portland, Oreg.

Application March 15, 1937, Serial No. 68,165

Term of patent 14 years

To all whom it may concern:

Be it known that I, Henry F. Phillips, a citizen of the United States, residing at Portland, in the county of Multnomah and State of Oregon, have invented a new, original, and ornamental Design for a Screw, of which the following is a specification, reference being had to the accompanying drawing, forming part thereof.

Figure 1 is a top plan view of a screw showing my new design, and Figure 2 is a perspective view of the same.

The dominant features of my design reside in the head portion of the screw.

I claim:

The ornamental design for a screw, as shown and described.

HENRY F. PHILLIPS.
